UNITED STATES PATENT OFFICE.

THOMAS LEWIS, OF NEW CUMBERLAND, OHIO.

TEMPORARY SHOCK SUPPORT.

Application filed March 15, 1923. Serial No. 625,361.

To all whom it may concern:

Be it known that I, THOMAS LEWIS, a citizen of the United States, residing at New Cumberland, in the county of Tuscarawas and State of Ohio, have invented certain new and useful Improvements in Temporary Shock Supports; and I do declare the following to be a full, clear, and exact description of the invention, such as will enable others skilled in the art to which it appertains to make and use the same.

My invention relates to improvements in devices to be used in properly forming shocks of corn, forming a temporary support for the shock until the latter has been tied.

The object of the invention is to provide a simply constructed and inexpensive, yet a very desirable support of the character set forth, which may be folded for easy withdrawal from the completed shock and for compact storage.

With the foregoing in view, the invention resides in the novel subject matter hereinafter described and claimed, the description being supplemented by the accompanying drawing.

Figure 1 is a side elevation showing the use of my invention.

Figure 2 is an elevation of the support independent of the shock.

Figure 3 is a vertical longitudinal sectional view.

Figure 4 is a horizontal sectional view as indicated by line 4—4 of Fig. 2.

In the drawings above briefly described, the numeral 1 designates a support shown in the form of a stake adapted to be driven into the ground, this stake being preferably formed of a length of angle metal. In the present showing, a pair of rigid arms 2 extend laterally in the same direction from the stake 1 and are formed by the ends of a metal bar which is bent around said stake and clamped frictionally against the same by a bolt 3 passing through the arms. This construction forms in effect a carrying collar for the arms 7 and permits vertical adjustment of said arms along the stake by loosening the bolt 3.

An arm-carrier 4 is mounted between the free ends of the arms 2 and preferably consists of an elongated metal plate having downturned ends 5 pivoted against the inner sides of the arms, by a bolt 6. This bolt is tightened sufficiently to bind the ends

of the carrier 4 frictionally against the arms 2, whereby the carrier is frictionally held in any position to which it may be turned, but may move about the bolt 6 as a pivot, when sufficient force is exerted.

A pair of horizontally swingable arms 7 are pivoted at 8 to the upper side of the carrier 4, these arms being adapted to be swung into divergent relation to form a crotch in and around which the stalks of corn may be piled. When the shock is completed and tied however and the stake is pulled from the shock, the arms 7 swing inwardly toward each other and at the same time move downwardly, the latter movement being permitted by the pivotal mounting 6 of the carrier 4.

Appropriate stops 9 are preferably employed for limiting the inward and outward swinging of the arms 7 and these stops may well be formed by passing a U-bolt 10 through openings in the carrier 4 and upsetting its ends.

After forming the shock around the temporary support, the upper end of the shock is contracted by means of an appropriate binding device D which includes a shock-encircling rope or the like R. After tying the shock, the device D is removed.

By employing a device constructed in accordance with my invention, it will be seen that shocks of corn or the like may be properly formed and temporarily supported in a rigid manner preparatory to tying. When the tying operation is completed, however, the device may be easily removed and used for forming the next shock. As excellent results have been obtained from the details disclosed, they may well be followed. However, within the scope of the invention as claimed, numerous minor changes may be made.

I claim:

1. A temporary shock support comprising a stake to be driven into the earth, a pair of arms intermediate the ends of said stake normally diverging from each other in a plane substantially at right angles to the stake, and means pivotally and frictionally mounting the arms on the stake for inward swinging toward each other, and downward swinging on a different axis to a position parallel with the stake, when the device is withdrawn from a completed shock.

2. A temporary shock support comprising

a stake to be driven into the earth, an arm carrier pivoted to said stake for folding vertically, and a pair of arms pivoted to said carrier for horizontal movement.

5 3. A temporary shock support comprising a stake to be driven into the earth, a pair of rigid arms extending from said stake, an arm carrier pivotally mounted between said rigid arms on a horizontal axis, and a pair 10 of horizontally movable arms pivoted to said arm carrier.

4. A structure as specified in claim 3; said arm carrier being formed of a metal plate with vertically bent ends pivoted to 15 said rigid arms.

5. A structure as specified in claim 3; said rigid arms being formed by the ends of a metal bar bent around the stake and bolted to the same.

20 6. A temporary shock support comprising

a stake to be driven into the earth, an arm carrier mounted on and adjustable along said stake, and foldable arms carried by said arm carrier.

7. A structure as specified in claim 3; 25 said rigid arms being formed by the ends of a metal bar bent around the stake and bolted frictionally against the same to permit vertical adjustment of said arms.

8. A temporary shock supporting device 30 comprising an elongated support, a collar surrounding and adjustable along said support, and pivoted arms carried by the collar to support a shock while forming the same, said arms being foldable when removing 35 the device from the shock.

In testimony whereof I have hereunto affixed my signature.

THOMAS LEWIS.
